UNITED STATES PATENT OFFICE.

FRANKLIN S. LAMSON, OF WASHINGTON, DISTRICT OF COLUMBIA.

PROCESS FOR MAKING CONCRETE STRUCTURES, DAMS, WALLS, BRIDGES, CONDUITS, SEWERS, PAVEMENTS, &c.

1,249,290.

Specification of Letters Patent. Patented Dec. 4, 1917.

Application filed June 23, 1906. Serial No. 323,159.

To all whom it may concern:

Be it known that I, FRANKLIN S. LAMSON, a citizen of the United States, residing at Washington, D. C., have invented a new and useful Improvement in Processes for Making Concrete Structures, Dams, Walls, Bridges, Conduits, Sewers, Pavements, &c., of which the following is a specification.

This invention relates to the making of concrete structures in which the fresh concrete is laid in advancing formation—as described in my application Ser. No. 299,800, (patented July 5, 1910, No. 963,159) and has for its object the formation of such structures by the use of such methods as will enable their construction with increased facility, rapidity and economy:—such methods as will allow the continuous performance by operative machines of each of the series of operations which combine to produce the structure; and as will admit of the uniting of plastic material with plastic and non-plastic material in monolithic construction.

The process described in said prior application included the method of emplacing layers of fresh concrete blocks at an angle from the horizontal of 45°, more or less.

In this application the process relates to methods which include the continuous use of operative machines in feeding the material to the mixer, in mixing said material, and in discharging the mixed material from the mixer in regular form and at once accurately emplacing it directly on, in or with the structure; to a method for discharging the freshly mixed concrete directly upon the structures being made in forms of successive layers which advance by regulated methods; to a method for uniting series of such freshly plastic advancing forms; to a method for supporting and regularly advancing movable inclosed concrete-making-and-emplacing plants upon such structures; to a method for compacting the freshly-emplaced concrete; to a method for emplacing non-plastic material with plastic concrete in regulated amounts; to a method for regulating the compression of the plastic surface of a structure.

In the accompanying drawings Figure 1 is a vertical section—with parts broken away—of a dam or weir in process of construction with a concrete-plant car shown as laying the concrete cover on the rock-fill;

Fig. 2 is a vertical transverse section on the line α α of Fig. 1, which shows, on the left, a section of steel framing being emplaced, in the center, rock-fill dump-cars (on trackage beyond the visible fill), and on the right, 60 a concrete-plant car as depositing concrete with the core-wall steel framework shown at 3' in Fig. 1; Fig. 3 is a plan view showing trackage for concrete and rock-fill cars, and Fig. 4 a side view of a movable trestle 65 with rock cars in position to dump, as at 1 in Fig. 3; Fig. 5 is a side view of a part of a steel-concrete bridge—with parts broken away, shown as supporting an operating construction-car with an arrangement 70 of material receptacles for continuous delivery, mixture and deposit, and Fig. 6 a detail view in perspective showing a section of a water-spraying pipe for forcible mixture of liquid cement with solid materials. 75

In the process described in the said prior application the fresh concrete blocks were to be conveyed from the mixers to the workmen to be emplaced by hand; the herein-described process consists in discharging 80 the fresh concrete from the mixers in continuous unbroken layers, and, in various methods, directly emplacing them on the structures.

The said prior application included in its 85 subject-matter the placing, and embedding in the concrete, of a metal framework which would bind together the included sections of concrete, and support the mold boards and on which framework a movable covered 90 work-inclosing frame would be supported; in this process a movable frame supported on trucks and rails on a suitable metal framework may carry the requisite construction plant—material receptacles, conveyers, 95 mixers, motive-power, and a regulated amount of material, and may be advanced in a regulated manner. Such advancing movement may be continuous, intermittent, or reciprocating, adapted to the requirement. 100 When a line of mixers—or a series of rows of mixers—are arranged consecutively, a stone-dumping conveyer or machine—or series of conveyers or machines—may be placed between each two units of the line—105 or rows of the series—to deliver such material in regulated amounts between the layers of plastic material. The impact of stone falling on soft material, and soft material falling on stone, layer upon layer, will unite 110

and compact the mass most thoroughly, with great economy in the amount of power required for the mixers. In many instances more than two-thirds of the bulk of the material may be non-plastic, as when the proportions are: cement 1, sand 2, gravel (or crushed stone commonly named aggregate) 3, stone 5, when the cement and sand—properly moistened and mixed—may be discharged from the mixer in a regular mass of progressive continuity, a regulated amount of gravel (wet or dry) to follow, and the proper amount of stone dropped upon and embedded in the plastic mass; such operations to be repeated as desired.

In the drawings, which illustrate the methods herein described, Fig. 1 is a cross-sectional elevation—with parts broken away to shorten the structure—of a dam or weir built on a sand and gravel foundation, as in a river bed where a rock foundation is found to be impracticable, which dam or weir consists of a series of concrete core-walls spaced at proper distances apart and having such spaces filled with broken rock or other suitable material and having such core-walls and rock-fills capped and bound together by a concrete cover of adapted quality and thickness; as shown in said figure the crest wall is provided on its up-stream side with a sloping talus of rock or rubble, and with sheet piling embedded in its base and suitably driven down into the underlying sand and gravel to prevent passage of seepage; the toe-wall is provided on its down-stream side with an apron of rock or rubble, such apron being level about three-fourths of its surface down and sloping the remaining distance, as shown; this wall is also provided with piling to prevent backward seepage undermining the wall at this point of water-passage from concrete cap to rock or rubble apron.

In this figure the section A A shows on the left a portion of a portable car-track framework 1, which forms part of the trackage system which supports construction-plant cars; the continuation of this line is shown as supporting the concrete-mixer car 2 which delivers the concrete in two regular layers which are compacted together and brought to contour by the following roller, as shown, in forming the concrete cap which covers the rock-fills and connects the three core-walls; intersecting this line on the left is a portable line of trackage, 1³, which is detachably connected to the permanent reinforce framework 3, shown as embedded in the concrete of the crest core-wall, which frame-work and trackage serve to support the dump cars which deliver the rocks at the site, and after the rock-fill is brought to contour—as is shown on the right of the figure where the frame 3¹ and trackage 1³ are in position for the middle core-wall—sustain

the concrete making and delivering plant car which builds the wall, such as the car 2³ on the right of Fig. 2 which embeds the framing between the opposite faces of the rock-fills. On the extreme right of section A A an elevated trackage and framework—also portable and which rests on the surface of the rock-fill—may support material-containing cars which deliver to the construction cars on the tracks 1³ alongside. In section B of Fig. 1, on the left, the rock-fill and concrete cap, with the toe-wall, its reinforce frame 3² and piling, are shown as completed; on the right the portable trackage-frame 1² is shown as resting on the slope of the completed apron and connected with the trackage 1⁴, which is a continuation of the line beginning at 1 on the left of the figure. Fig. 2 is a transverse elevation on the line x—x of Fig. 1, in which—on the left—a crane 2¹ is shown as supported on trackage detachably connected to the top of the steel-reinforce framework and in the act of lowering a section 3³ of such framework to position in extension thereof; centrally in Fig. 2 dump cars 2² containing material for the rock-fill are shown as apparently on the trackage of framework 3¹, but their operative position would be on a slightly lower level on portable trackage resting on the top of the rock-fill in part and in part on the movable section 1⁴ of portable framing shown in Fig. 4, and centrally in the plan view in Fig. 3; on the right in Fig. 2 the construction-car 2³ is shown as delivering concrete and rocks alternately in embedding the reinforce framing 3¹ between the faces of rock-fill—central in Fig. 1—in the formation of the middle core-wall; the supply of material to car 2³ may be from cars on elevated trackage—as 1' in Fig. 1—by trolley buckets from any position, or otherwise. Fig. 3 is a plan showing different trackage methods usable in supplying and emplacing the required construction material, the trackages 1 and 1⁴ being supported on the rock-fill or the earth, and 1³ on the reinforce framing for the core-walls; steel tie-rods a, suitably spaced apart, may be embedded in the concrete cap covering the structure between the core-walls, serving to aid in binding them together in strong construction. In Fig. 4 material dump-cars 2² are shown as supported on trackage sustained on the surface of the rock-fill and on the left on the movable car-supporting frame provided with wheels or rollers which may travel on sectional trackage or planking, which may be advanced as the fill is completed; the surface trackage also to be supplied in sections as the work progresses.

Fig. 5 is a side elevation of a twin-pier abutment and half-span of arch of a steel-concrete bridge which illustrates the application of my angle-truss-brace methods in

such complex construction, in which the dotted lines indicate the embedded system of steel reinforce, the various parts being strongly connected in manner and method as herein described. On the right of the figure a portion of the railing is broken away to show a construction-plant car supported on tracks connected to the steel framework, which illustrates an arrangement of material-supply receptacles as adapted for the continuous delivery of the material when the mixing is to be accomplished by the impact of strongly forced water-spray as the separate streams of cement, sand, etc., pass from their respective delivery-openings on their way to the structure, as described.

When preferred the mixed cement and sand (or cement and sand unmixed) may be discharged dry, and forcibly water-sprayed as it passes to the structure; the gravel and stone also passing through spray in falling if desired. The force of such spraying of the cement and sand to be adapted to the requirement that such spraying carry the cement and sand to contact with and among the gravel as it falls on the structure with thorough mixture, the regularly delivered stone, in falling, being embedded in the plastic mixture on the slope, and covered by the succeeding plastic mixture.

The methods of the discharge and delivery of the material may be varied to suit the requirements of the structures, and mechanical devices may be used to cause the proper mixing of such material as it passes to the slope if needed.

When the freshly-plastic concrete is to be laid in a slope of step formation with a continuous forward delivery, each of a series of advancing mixers discharges its product in a layer at a regulated distance back of its predecessor, the whole forming a series of superimposed plastic layers which are advanced simultaneously, rising by steps layer upon layer. When two such series of advancing forms of freshly-plastic material advance toward each other and unite, it is without joint-monolithic union.

With a series of movable mixers arranged upon said framework to deliver their product beneath them by regulated method, such delivery may be so made as to form a slope at one end of a structure (as a dam or conduit), and by regulated advancing delivery continuously advance the face of such slope, from bottom to top, to the other end.

When preferred (as on long slopes) the movable mixers—instead of having continuous forward movement—may advance with a reciprocal movement, alternately advancing the delivery to the foot of the slope and retiring it to the top, with a progressive advance of the whole slope; such method enabling rapid construction with smaller

plants, the enlargement of mixers in a less number thereof reducing the number without decreasing the delivery of the product. Such movable mixers may be provided with adapted receptacles for material, which material may be supplied thereto from detachable trucks movable on rails supported on the said framework; from such receptacles such material is to be conveyed in regulated amounts to the mixers or delivering devices for emplacement upon the structure. When the construction plant is arranged upon a frame supported on trucks, movable on rails connected to said framework, such detachable trucks may also supply the material for the concrete to similar adapted receptacles upon such movable frame, from which receptacles such material may be similarly conveyed in regulated amounts. When so desired the cement and sand only may be conveyed to the mixers, the regulated amounts of gravel and stone being conveyed to, and dropped through, openings in the movable frame directly upon the structural formation, being regularly combined with the cement and sand in the forward progress of the plant; or, as a variation, the cement, sand, gravel and stone may be separately delivered, the cement and sand—in falling—being horizontally struck by strongly forced water-spray which mingles and combines the material as it drops on the structure; the gravel being preferably continuously delivered, and the stone intermittently, in regulated ratio.

The falling of heavy material on the advancing slope of freshly plastic concrete serves to thoroughly compact the mass, the stone being carried by gravity to place, and the jarring impact causing perfect union. In structures which must sustain great pressure (dams, bridges, etc.) the said metal framework is to be anchored to the rock bed by steel construction adapted to the estimated stress, and such anchorage is to be thoroughly embedded in the plastic concrete to prevent corrosion. In such a process the construction of the necessary framework, and of the inclosing mold-boards, goes forward in advance of the concrete work, the said mold-boards being held in place and supported by the said framework. Such framework may be made in sections of different levels, as for walls of buildings, when the frame may be carried story-high at a time, and the concrete emplaced; but when practicable (as in retaining-walls, conduits, etc.) such frame is preferably set up to full height at one or both ends of a structure (and if desired at one or more points between), the necessary tracks, mold-boards and construction-plant emplaced, and the full construction advanced simultaneously.

The combination of plastic concrete and steel united (to jointly carry the load) was

described in my prior application Ser. No. 119,673 (patented Nov. 5, 1907, No. 870,370; in the above-named prior application 299,800, Patent No. 963,159, July 5, 1910, the introduction of truss-brace metal frames in freshly-plastic concrete is also described. In such joint steel-and-concrete structures it is of much importance that the method of the steel framing shall be such as to best enable the structure to withstand the stress of extreme pressure (earthquake shocks, tornado blasts); it is also of great importance that the members of such steel framing shall be of such form, and so placed, as to enable the passage of the freshly-plastic concrete into contact and jointure with every exposed part of such frame. To accomplish this double purpose the said frame may be made of members which are connected together so as to form a system of truss-brace framing in which each member is set vertically edgewise, and each brace-member set longitudinally at an angle from the horizontal of about 60° to 70°, more or less; the whole frame to be suitably connected with vertical and horizontal supports, bearings, ties, bolts and rivets. Such members may be flat, J-shape, T-shape, + -shape, L-shape, but set vertically edgewise to enable the plastic material to pass to contact with every exposed part.

The vertical position of the web of each member—as embedded in the concrete—best enables a structure to withstand the effect of thrusts from beneath, or otherwise; and the method of framing best enables the structural unit to withstand every stress.

As a means to aid in the transfer of the said mold-boards from the rear to the front—or for other construction purposes, detachable scaffolding may be connected with, and supported by, the said metal framework, the means of such connection being similar to those used in the support of the said series of mold-boards, but specially adapted to the purpose in view.

I am aware that prior to my application the emplacement of fresh concrete roughly on beds or in molds was common, such placed material being worked to desired forms by tools, or rammed in trenches or molds in layers of more or less approximate regularity; that such approximately regular layers have been formed (by hand work of a row of workmen) in sloping molds, as in the patents to Ransome, 353,500, 515,014, 517,808.

Such forming methods I do not claim.

By reference to the above-named Patent No. 963,159 (paragraph next preceding claims) it appears that the disclosure covers "continuous movement of materials to union and of the product of such union to emplacement and compaction while plastic." In this application additional economy and rapid-

ity of construction for large structures is especially shown in the improved methods for producing such continuous movement of materials to mixture, and of mixture to compacted deposit.

I claim:

1. The method of mixing concrete which consists in wetting the dry cement to liquid consistency and moving the inert material within a spray or shower of such liquid cement. 75

2. The method of mixing concrete which consists in producing a water-spray of shower, moving dry cement within such spray or shower (and subject thereto), and moving the inert material within, and subject to, full contact with the thereby produced liquid cement. 80

3. The method of mixing concrete which consists in moving a stream or streams of inert material and causing liquid cement to envelop such inert material. 85

4. The method of mixing concrete which consists in moving a stream or streams of inert material, moving a stream of dry cement adjacent to such stream or streams, and by force causing water to envelop the cement, and the produced liquid cement to envelop the inert material. 90

5. The process of producing a plastic mixture which consists in discharging dry material and liquid from separate confinement in sources of supply, and bringing such substances together while moving from separate points of delivery into permanent position. 95

6. The process of producing a plastic mixture which consists in discharging liquid and dry materials from confinement in separate sources of supply, bringing said materials together while in motion after passing from their points of separate discharge from such confinement, and continuously depositing the mixture thus formed. 100

7. The process of producing and applying a plastic mixture which consists in separately conducting in continuous movement liquid and dry material from separate sources of supply movable in unison, bringing such materials together while in motion and continuously depositing the mixture with compacting force during movement of said sources of supply. 110

8. The method of mixing concrete which consists in separately delivering (from separate sources of supply) streams of relatively dry comminuted material (cement, sand—separate or mixed) and liquid, and causing the liquid—forcibly projected, to envelop such comminuted material after the streams pass from their points of delivery. 120

9. The method of mixing concrete which consists in separately delivering relatively dry cement and sand, causing projected water-spray to envelop the cement, the pro- 125

duced liquid cement to envelop the sand, and forcing this mixture into intimate contact with the separately delivered aggregate.

10. The method of mixing cement consisting in separately feeding dry materials to the formation, and simultaneously causing forcibly propelled water-spray to carry cement into contact and mixture with the other material or materials as they pass to 10 and are deposited on the formation, whereby liquid cement is applied to the solid material or materials being deposited.

11. The method of mixing concrete materials consisting in separately feeding dry 15 cement and dry sand to the formation, and simultaneously causing forcibly-propelled water-spray to carry the cement into contact and mixture with the sand as it passes to the formation, whereby liquid cement is applied 20 to and mixed with sand.

12. The method of forming concrete structures, consisting in separately feeding dry cement, dry sand and dry aggregate to the formation, and causing forcibly-propelled water-spray to carry the cement into contact and mixture with the sand, and the cement and sand to mixture with the aggregate while in motion.

13. The method of mixing concrete material consisting in separately feeding to 30 the formation a dry cement-and-sand mixture and a dry aggregate, and causing forcibly-propelled water-spray to carry the cement and sand mixture into contact and 35 mixture with such aggregate as they are fed to the formation.

14. In a process for making concrete structures, the steps of separately feeding to the formation dry cement and sand by gravity, by gravity feeding aggregate, and 40 causing forcibly propelled water-spray to carry the cement and sand into contact and mixture with such aggregate as it passes to the formation and is deposited thereon.

15. In a process for making concrete 45 structures, the steps of separately feeding to the formation dry cement and sand by gravity, by gravity feeding aggregate, and simultaneously causing forcibly-propelled water-spray to carry the cement and sand 50 into contact and mixture with such aggregate as it passes to the formation and is deposited thereon, and by gravity feeding stone thereto, whereby the deposited plastic material is compacted by the impact of falling 55 stone being embedded therein.

16. In a process for making concrete structures employing a concrete material-containing, proportioning and discharging plant on a frame, the steps of moving such 60 a plant forward with regulated method, discharging the dry material in regulated proportions, and forcibly spraying with regulated water-volume the discharged material as it passes to and is deposited on the 65 structure.
